UNITED STATES PATENT OFFICE

160,771

COVER FOR SUGAR BOWL

R. Guy Cowan, Fayetteville, N. Y., assignor to Onondaga Pottery Company, Syracuse, N. Y., a corporation of New York

Application December 6, 1949, Serial No. 6,457

Term of patent 14 years

(Cl. D44—15)

To all whom it may concern:

Be it known that I, R. Guy Cowan, a citizen of the United States, residing at Fayetteville, State of New York, have invented a new, original, and ornamental Design for Cover for Sugar Bowl, of which the following is a specification, reference being had to the accompanying drawing, forming a part hereof.

I claim:

The ornamental design for a cover for sugar bowl, as shown.

R. GUY COWAN.
